UNITED STATES PATENT OFFICE.

HARRY H. FOREMAN, OF MAZEPPA, MINNESOTA, ASSIGNOR OF ONE-HALF
TO WILLIAM FOREMAN, OF SAME PLACE.

KETTLE-COVER.

SPECIFICATION forming part of Letters Patent No. 595,454, dated December 14, 1897.

Application filed June 3, 1897. Serial No. 639,293. (No model.)

To all whom it may concern:

Be it known that I, HARRY H. FOREMAN, a citizen of the United States, residing at Mazeppa, in the county of Wabasha and State 5 of Minnesota, have invented certain new and useful Improvements in Kettle-Covers; and I do declare the following to be a full, clear, and exact description of the invention, such as will enable others skilled in the art to 10 to which it appertains to make and use the same.

My invention has relation to kettle-covers.

The object of the invention is to provide a cover of this character whereby the kettle may be filled with water without the necessity of removing the cover and at the same 15 time the steam rising from the water within the kettle will be prevented from escaping through the cover.

With this object in view the invention consists in certain features of construction and combination of parts which will be hereinafter 20 fully set forth.

In the accompanying drawings, Figure 1 is a longitudinal sectional view of a kettle-cover 25 constructed in accordance with my invention, and Fig. 2 is a detail perspective view of the strip hereinafter described.

In said drawings, 1 denotes the cover, which is of conical form and is provided with a tubular neck 2. Secured around the cover, near 30 its upper end, is a laterally-projecting flange 3, provided with a downwardly-extending ring 4, which is adapted to fit within the kettle.

5 denotes a valve adapted to close the lower tubular end of the cover. 6 denotes a spring the lower end of which projects through said 35 valve and is headed, and 7 denotes a strip secured within said cover and to which the up-

per end of the spring is attached. This strip 40 has struck from its body tongues 8, and the end of the wire forming the spring is engaged with one tongue, which projects downwardly from the under side of the strip, while the top coil of the spring is engaged with the 45 other tongue, which projects upwardly from the upper side of the strip. These tongues, after the spring has been engaged therewith, are bent around the spring and securely retain it in position.

50 In operation when it is desired to fill the kettle water is poured into the funnel-shaped cover and the weight of the water will depress the valve and allow the water to flow into the kettle, when under the action of the 55 spring the valve will be returned to its normal position, thus closing the cover and preventing the escape of steam or the kettle boiling over.

Having thus described my invention, what 60 I claim, and desire to secure by Letters Patent, is—

A cover for kettles comprising a funnel-shaped body, a valve to close the neck of the funnel-shaped body, a spring having one end 65 connected with the valve, and a strip secured within the body and provided with tongues struck up from the strip, one extending downwardly and the other upwardly, and bent around the upper end of the spring, substantially as set forth.

70 In testimony whereof I hereunto affix my signature in presence of two witnesses.

HARRY H. FOREMAN.
